UNITED STATES PATENT OFFICE.

PHILIP H. BEVIER, OF BROOKLYN, NEW YORK, ASSIGNOR TO NATIONAL FIRE PROOFING COMPANY, OF PITTSBURGH, PENNSYLVANIA, A CORPORATION OF PENNSYLVANIA.

COMPOSITE FLOOR STRUCTURE.

Application filed May 8, 1924. Serial No. 711,840.

The present invention relates particularly to composite floor structures, and more particularly to an improved tile for use therein, whereby the strength of the floor is materially increased.

It is well known that ordinary hollow tiles have a materially greater strength in compression than in tension. It is therefore one of the objects of the present invention to so form a tile that when in position in a floor structure, the load will be effectively transmitted to portions of the tile and the composite structure capable of most efficiently carrying the same.

Another object of the present invention is to reinforce the upper wall of each of the hollow tiles to prevent accidental breaking through thereof by providing reinforcing means of such nature that a balanced tile structure is produced having a comparatively uniform wall thickness with narrow bracing webs disposed to afford maximum protection in the event of fire.

In the accompanying drawings, there are shown for purposes of illustration only certain preferred embodiments of the invention, it being understood that the drawings do not define the limits of my invention, as changes in the construction and operation thereof may be made, without departing from the spirit of the invention or the scope of the broader claims.

In the drawings:

Figure 1 is a perspective view of one form of tile;

Figure 2 is a perspective view of a slightly modified form of tile; and

Figure 3 is a section through a composite floor structure taken transversely of the tiles.

The tile of the present invention while adapted to different uses is specifically adapted for use in a composite floor structure of the character illustrated in the patent to Toupet, No. 1,404,710 of January 24, 1922. In such a structure, the main compression member is composed of tiles which are preferably of burnt clay, although cement or concrete tiles may be used.

These tiles, which are indicated generally at 2 in the drawings, are laid in longitudinal parallel courses, the tiles in each course being placed end to end, but adjacent courses being separated laterally from each

other, due to the tile construction, as clearly indicated in Figure 3.

Each of the tiles preferably comprises a top wall 3 and a bottom wall 4, both of which are of substantially uniform thickness throughout the width thereof and both of which are substantially flat to provide opposed substantially parallel faces. The tiles are generally rectangular in cross section, but are preferably formed with offset side walls 5. Any one or all of the walls may be provided with grooves 6, adapted to secure proper interlocking between the adjacent tiles or between the covering materials and the tiles. The offset side walls are formed by providing laterally projecting bottom ribs 7, whose lower surfaces form continuations of the bottom of the tile. These bottom ribs are of a width equal to substantially half the width of the space desired between adjacent courses of tile, and which are adapted to be filled with suitable plastic material 8, reinforced with metal. This plastic material should be of carefully selected composition, possessing substantially the same strength or resistance to compressive loads per unit of area as the compressive resistance of the tile, whereby the floor structure is of uniform strength.

The side walls of the tile are formed with longitudinally extending grooves 9, preferably somewhat dovetailed in form and forming an effective bonding means for the plastic fillings 8. They also give these fillings a shear engagement with the tiles, whereby the greater area of the structure is placed in shear, and they also form supporting means for metal reinforcements or ties in the manner hereinafter more fully pointed out.

It will be apparent that, if desired, however, the grooves 9 may be omitted entirely and the grooves 6 relied upon for effectively interlocking the tiles and the plastic filling.

When laid in position, the projecting ribs 7 are in abutting engagement, thereby providing a continuous bottom surface to receive plaster or the like, and at the same time forming a closure for the bottoms of the spaces between the tile courses, enabling the plastic filling to be easily poured into position.

It is well recognized that the top and

bottom walls of an ordinary hollow tile constitute the weak points thereof, unless the same are effectively reinforced. Without reinforcement or a disposition of the body 5 of the tile placing a substantial portion thereof in compression, such walls may be easily broken through. In the present construction, in order to effectively reinforce the top wall 3 and prevent crushing or breaking through thereof, there are provided bracing webs 10, extending divergently from the center of the upper wall and the side walls 5, preferably adjacent the bottom of the grooves 9.

15 A second set of bracing webs 11 extend convergently from the points of intersection of the bracing webs 10 with the side walls 5 to the center of the bottom wall 4. By reference more particularly to Figure 3, it will be apparent that a load represented by the arrow L in said figure will be transmitted through the bracing webs 10 to the plastic fillings 8, as indicated by the arrows L'. This will place the upper portion of the tile, including the bracing webs 10, in compression. This will develop compressive forces which will be transmitted to the plastic fillings 8 from opposite sides thereof effective for, in turn, placing such fillings 20 under compression, in which they are capable of withstanding a maximum load. Due to the divergency of the bracing webs 10, there will be a resultant downward load as represented by the arrows 7. In order to 25 provide a direct reinforcement for such loads, metallic reinforces 12 may be effectively utilized, serving as tension members. These tension members may be mounted, as suggested in the patent referred to, being 30 normally held in position by straps or stirrups 13, having hooked upper end portions 14, which engage the bottom walls of the longitudinal grooves 9. In this manner, a maximum floor strength is provided. The 35 bracing webs 11 extending from the bottom wall to the point of intersection of the webs 10 with the side walls serve as bracing means for the bottom wall.

In floor structures of the character contemplated by the present invention, it is 40 customary to so proportion the strength of the respective parts that the neutral axis will be slightly above the median plane of the tiles. It will be noted that the grooves 45 9 are located so as to be above the neutral axis and that the bracing webs 10 and 11 intersect the side walls at a point such that the relatively heavier body provided at these points will be above the neutral axis 50 and thereby effective in compression for carrying maximum loads.

This constitutes an important advantage 55 of the present invention. The bracing webs also form a bilaterally symmetrical tile 60 which while not reversible with respect to

its upper and lower walls is reversible end for end, thereby facilitating laying thereof. The bracing webs are also so disposed that a maximum amount of material is effective 70 in case of fire between the top and bottom walls and in the event of breakage of either of these walls. The bracing webs also render the tiles largely sound proof, due to the fact that they break the interior of the tiles up into separate cells, thereby compelling sound vibrations to pass through a number of separated walls.

It will be understood that the present floor structure is constructed in accordance with what is known as the straight line formula, 80 in which the amount of tile material in compression above the neutral axis of the floor, multiplied by the average compressive stress to which such matter is subjected, is equal to the area of the reinforced metal 85 in tension, multiplied by the allowable tension stresses on such reinforcing material. The amount of material in compression thereby becomes of considerable importance, as is also the location of the bracing webs 10, 90 tending to directly transmit such compressive stresses to other portions of the composite floor structure which are themselves in compression, rather than to some point below the neutral axis of the tile where 95 the tile is in tension.

The advantages of the present invention arise from the provision of a composite floor structure of the character set forth composed 100 of tiles constructed to have a substantial portion thereof in compression and to transmit compressive stresses directly to the side walls of the tile and to the plastic fillings therebetween.

I claim:

1. A hollow tile for floor structures, having substantially flat upper and lower walls, side walls extending between said upper and lower walls, bracing webs extending divergently from the center of the upper wall to the side walls, and bracing webs extending convergently from the points of intersection of the first mentioned bracing webs and side walls to the center of the lower wall, substantially as described. 105

2. A hollow tile for floor structures, having substantially flat upper and lower walls, side walls extending between said upper and lower walls, bracing webs extending divergently from the center of the upper wall to the side walls and intersecting the side walls above the computed neutral axis of the tile, and bracing webs extending convergently from the points of intersection of the first mentioned bracing webs and side walls to the center of the lower wall, substantially as described. 110

3. A hollow tile for floor structures, having substantially flat upper and lower walls, side walls extending between said upper and 115

- lower walls, bracing webs extending divergently from the center of the upper wall to the side walls, and bracing webs extending convergently from the points of intersection of the first mentioned bracing webs and side walls to the center of the lower wall, said tile being bilaterally symmetrical and having grooves in certain of the walls thereof, substantially as described.
4. A hollow tile for floor structures, having substantially flat upper and lower walls, side walls extending between said upper and lower walls, bracing webs extending divergently from the center of the upper wall to the side walls, and bracing webs extending convergently from the points of intersection of the first mentioned bracing webs and side walls to the center of the lower

wall, said tile having bottom ribs extending outwardly therefrom in the plane of the lower wall, substantially as described.

5. A hollow tile for floor structures having substantially flat upper and lower walls, the upper wall being thicker than the lower wall, side walls extending between said upper and lower walls, bracing webs extending divergently from the center of the upper wall to the side walls, and bracing webs extending convergently from the points of intersection of the first mentioned bracing webs and side walls to the center of the lower wall, substantially as described.

In testimony whereof I have hereunto set my hand.

PHILIP H. BEVIER.
